TOY MISSILE AND LAUNCHER

Josiah Morrison Barr, Manhattan Beach, Calif., assignor to American Machine & Foundry Co., a corporation of New Jersey

Filed July 10, 1961, Ser. No. 122,814

7 Claims. (Cl. 46—77)

This invention relates to toy missiles and more particularly to the equipping of toy aircraft, or other toys, with releasable, self-propelled missiles and missile launchers.

It is an object of this invention to provide a self-propelled, releasable toy missile and a missile launcher for such toys as toy aircraft, or other movable or stationary toys, such as a toy comprising only a missile launcher equipped with a plurality of missiles.

It is also an object of this invention to provide means for mounting and releasing toy missiles from toy aircraft and other toys.

It is still another object of this invention to provide a remote control mechanism for releasing self-propelled missiles from a missile launcher.

Additional objects of this invention will be understood more clearly from the description of the invention given in connection with the accompanying drawings.

The novel features which are believed to be characteristic of the invention, both as to its organization and method of operation, together with further objects and advantages thereof, will be better understood from the following description considered in connection with the accompanying drawings in which several embodiments of the invention are illustrated by way of example. It is to be expressly understood, however, that the drawings are for the purpose of illustration and description only, and are not intended as a definition of the limits of the invention.

FIG. 1 is a perspective view of a toy aircraft with the missiles mounted on the wings of the aircraft.

FIG. 2 is a top plan view of a missile.

FIG. 3 is a sectional view of a missile, missile launcher and of the wing taken along line 3—3 shown in FIG. 1.

FIG. 4 is a transverse sectional view of the missile, missile launcher, and of a string used for releasing the missile from the launcher.

FIG. 5 is a perspective view of a stationary missile launcher.

FIG. 6 is a perspective view of missile launching, or release, mechanism.

FIG. 7 is a perspective view of a toy automobile with two missiles mounted on the roof of the car.

FIG. 8 is a side view of the missile release mechanism for releasing missiles when they are mounted on toy vehicles, such as the car illustrated in FIG. 7.

The missile launcher can be mounted either on a toy aircraft or on some other stationary or moving toy, as will become apparent from what follows:

Referring to the drawings, the toy aircraft is illustrated at 10. It is a monoplane having wings 12 and 14, fuselage 16, engine 18, propeller 20 and a tail portion 22 with appropriate rudder surfaces 24 and 26 for controlling the flight of the aircraft. The aircraft is provided with control wires 28 and 29 for controlling the flight of the aircraft and it is also provided with a missile release string 30. One end of said string is held in the hand of the operator of the aircraft and the opposite end of the string is attached to the tip of wing 14 at a point 32, with the result that string 30 extends almost through the entire length, or span, of the wing sections 12 and 14 and beyond to the operator. Two missiles 34 and 36 are mounted under the wings and these missiles are releasable by

2

pulling on string 30 in the manner which is described more in detail below.

The top plan view of the missile is illustrated in FIG. 2. The missile includes a central, hollow tubular member 200, which, in the preferred form, is a slotted tube, a front finger, or impact rod 201, which fits directly into the central tube 200 with its inner end 202. Finger 201 and tube 200 are provided with slots to accommodate a front flight stabilizer 204 which is provided with a flat surface bounded by diverging edges 205 and 206, and converging edges 207 and 208. The central tubular member 200 and the front impact rod 201 thus are connected to each other not only by slipping rod 201 into the hollow cylinder 200, but by also interconnecting these two members by means of the flight stabilizer 204, all three members 200, 201 and 204 forming a rigidly connected assembly. The entire missile may be made either of wood or synthetic plastic, in which case it may be injection molded by using high impact styrene, high density polyethylene or acrylonitrile-butadiene-styrene.

The central tubular member 200 is provided with a slot 210 which extends from end-to-end of tube 200, terminating the rear end 211 and the front end 212, which are produced by the insertion of rod 201 and stabilizer 218 into tube 200. Slot 210 is used for inserting the missile launcher 300, FIG. 3, into the slot in the manner indicated in FIG. 3. The missile is also provided with a helical coil spring 214 which forms a sliding fit within tube 200. Tube 200 is connected to the flight tail stabilizers of the missile including three tail stabilizers 216, 217, and 218, which are rigidly connected by means of the front extensions, such as extension 220 on stabilizer 217, to the rear end of tube 200. The missile launcher 300 is cemented to the wings 12 and 14 of aircraft 10 in the manner illustrated in FIG. 3. The launcher 300 forms a sliding fit with slot 210 in tube 200.

In order to mount the missile on the wings of the aircraft, spring 214 is slid to the front portion of tube 200, and it is thus compressed in the manner indicated in FIG. 3. Spring 214 is held in a compressed state by the front edge 302 of the missile launcher. The rear edge 304 of the launcher engages the rear edge 211 of the missile, and the missile is thus held securely on the launcher because of the pressure exerted by spring 214 on the front edge 302 of the launcher and the pressure engagement between the edges 304 and 211.

Missile launcher 300 is provided with an orifice 306 positioned close to its lower edge 308 and rear edge 304 and string 30 passes through orifice 306. The path followed by string 30 in passing through orifice 306 is illustrated in FIG. 4 where it is indicated that string 30 follows a U-shaped path 400 because orifice 306 and the lower edge 308 of the missile launcher extends into the tubular member 200 to such an extent that orifice 306 is positioned at the lower edge of the missile slot 210.

It, therefore, follows that the missile can be released by pulling the string. When a pull is exerted on string 30, the string will straighten itself out along a straight line path and thus eliminate the U-shaped portion 400. When this takes place, then string 30 will exert a pressure on the rear end of tube 200, and this will release edge 211 from its pressure engagement with the edge 304 of the missile launcher 300, thus releasing the missile by slipping the rear portion of the missile from the launcher. The compressed spring 214 will then at once be free to expand and such expansion of spring 214 will impart a very high forward velocity to the missile because of the pressure exerted by the spring on the front edge 212 of the missile, with the result that the missile will fly ahead of the plane, converting the potential energy of the spring into the high kinetic energy of the missile.

Because of the flight stabilizer 204 and the three flight stabilizers 216, 217 and 218, the missile will have good dynamic stability and still follow a trajectory of its own immediately upon leaving the plane.

It is possible to release either one or two missiles simultaneously by pulling on string 30. If only a slight pull is exerted on string 30, then only the nearest missile 36, FIG. 1, is released. However, if a strong pull is exerted on string 30, then both missiles are released simultaneously.

FIG. 6 also illustrates a mechanism for releasing one missile at a time when the missile launcher includes a plurality of missiles. This type of missile launcher mechanism can also be used on aircraft when a plurality of missiles are mounted. This type of release mechanism will be described later.

FIG. 5 illustrates either a stationary or rotatable missile launcher mounted on a stand 500. The vertical column 501 may be either a stationary or rotatable column. On top of the column there is mounted a plate 502 having a plurality of vertical bars 503-508, which correspond to the bar 300 in FIG. 3. The only difference between the mounting of the missile in FIGS. 1-3 and that illustrated in FIG. 5 is that while in FIGS. 1-3, bar 300 is suspended from wing 12 or 14 and is hanging down from the wing; 25 in FIG. 5 bars 503-508 rest on plate 502 and project upwardly from plate 502. In other words, the missile launcher of FIGS. 1-3 has been inverted, or turned, 180° and the functioning of the launcher otherwise is identical to that illustrated in the earlier figures. String 510 corresponds to string 30 in the earlier figures and it performs the same function as string 30 in the earlier figures. The missile launcher of FIG. 5 can be made rotatable by rotating column 501 either by means of a spring or a string which can be wound around column 501. Also, two 35 strings can be wound around column 501, one string being wound in a clockwise direction while the other is wound in a counter-clockwise direction, so as to turn this column either in a clockwise direction or a counter-clockwise direction, thus aiming the launcher. This is illustrated by 40 strings 517 and 514.

In FIG. 5, string 510, as a rule, will release all the missiles at the same time. A different arrangement may be used for releasing the missiles, in which case only one missile is released at a time, and this is illustrated in FIG. 6.

Referring to FIG. 6, plate 600 corresponds to plate 502 in FIG. 5 and the vertical bars 601-604 correspond to the vertical bars 503-508. The missile shafts are illustrated at 605-608. A raised boss 610 is provided on plate 600 and plate 600 is also provided with rectangularly-shaped bosses 611, 612 and 613, which are mounted anywhere between the bars 601 and 604, with one boss being mounted between the two adjacent rectangular bars 601-604. The missile launcher mechanism is then provided with a string for each individual missile, four strings 614, 615, 616 and 617 being illustrated in FIG. 6, because four missiles are illustrated in the same figure. String 614 then passes through holes 620, 621 and 622 of the vertical bars 601, 602 and 603. It then passes through the upper hole 623 of bar 611 and then through the upper hole 624 of bar 604. When string 614 is pulled it will have no effect on the missiles 605, 606 and 607, but it will release missile 608 because the string will be tightened and will follow a straight line path indicated by dotted line 625 which raises the tail end of the missile and thus releases it from bar 604 in the manner described previously.

The same is also true of all the remaining strings 615, 616, and 617, which will release their own respective missiles when they are pulled either simultaneously or in succession, depending upon the desire of the operator to release either one missile at a time or all of them simultaneously.

FIG. 7 illustrates the mounting of two missiles on a toy car 700, with the vertical plates 701 and 702 being 75

mounted on the left and right sides respectively on top 704. Two strings 705 and 706 are provided for releasing the missiles and the release mechanism is also provided with brackets 710 and 711 which correspond to brackets 516 and 518 in FIG. 5. The strings then pass through an opening in a bushing 708 and these strings 705 and 706 are also illustrated in FIG. 8 when they are connected to a crank shaft 800. Crank shaft 800 is geared by means of gears 801 and 802 to a rear axle 803 of the toy car and when the toy car is actuated by a suitable mechanism such as a spring, axle 805 is rotated, with the result that the crank shaft 800 is also rotated through gears 801 and 802. When the crank shaft reaches its lowest position with respect to the top of the car, strings 705 and 706 are tightened, with the result that the missiles are released. In this case, the two missiles are released simultaneously, but they can be released separately by providing separate releases for each missile of the type illustrated in FIG. 8.

What I claim as new is:

1. A toy missile launching apparatus comprising
  - (a) a missile launcher including front and rear missile-engaging members spaced from each other by a fixed distance;
  - (b) a missile having a central hollow member,
  - (c) a slit in said hollow member for receiving said front and rear members, said slit having front and rear edges;
  - (d) a helical compression spring forming a sliding fit with, and mounted within, said hollow member,
  - (e) said compression spring being compressed in the forward portion of said hollow member when said missile is mounted on said launcher with the aid of said slit and said members, with the rear end of said compression spring engaging said front missile-engaging member and the rear edge of said slit engaging the rear missile-engaging member, and
  - (f) missile releasing means for sliding said missile off said rear member for releasing said missile from said launcher.

2. The toy missile launching apparatus as defined in claim 1 in which said missile releasing means includes a recess positioned in and close to the outer end of said rear missile-engaging member, a string passing through said recess, said string following a U-shaped path at the point of passing through said recess and through the adjacent portion of the slot of said missile, said string, when pulled, releasing said missile from said launcher and said front and rear members by pushing said missile off said rear member and by launching said missile in forward direction from said launcher because of the release and pressure of said spring on said front member and also on said missile, whereby the potential energy of the spring is converted into the kinetic energy of said missile.

3. The missile launching apparatus as defined in claim 1 in which said missile releasing means also includes remote control means for releasing said missile from said launcher.

4. A toy aircraft comprising a wing, a missile launcher mounted under said wing, said launcher comprising a substantially rectangular plate having front and rear edges and a detent in the vicinity of the rear edge and bottom of said rectangular plate, a self-propelled missile mounted on said plate, said missile having a central tube with a slit extending through the length of said tube, a helical coil spring mounted in a sliding engagement with said tube, and front and rear flight stabilizing members connected to said tube, said rectangular plate fitting into said slit and into said tube when said missile is mounted on said plate with the coil spring being compressed between the front end of said tube and the front edge of said plate, and the rear end of said tube engaging the rear edge of said plate, and a string passing through said detent for remote control release of said missile from said plate.

5. A toy missile comprising

- (a) a single stage missile, said missile including
- (b) a hollow central member, and

- (c) a helical spring mounted in sliding engagement within said member, said spring constituting a part of said missile and flying with said missile upon release of said missile,
  - (d) said helical spring extending through the greater part of the length of said central member and
  - (e) a front impact rod at the front end of said missile closing off the front end of said hollow central member, and
  - (f) flight control surfaces at the rear end of said central member closing off the rear end of said central member,
  - (g) said spring being sealed in said hollow central member by said impact rod and said flight control surfaces.
6. A toy missile as defined in claim 5 which includes
- (a) a slit in said hollow central member,
  - (b) a missile launcher comprising a rectangular elongated member fitting into said slit,
  - (c) said elongated member having a length shorter than the length of said slit,
  - (d) said elongated member compressing said spring

5

10

15

20

into the front portion of said hollow central member when said missile is mounted on said missile launcher with the aid of said slit.

7. A toy missile as defined in claim 5 and including further

- (a) a missile launching member; and
- (b) a slit extending through the length of said central member, said slit accommodating said missile launching member for engagement with and compression of said spring when said missile is mounted on said missile launching member.
